UNITED STATES PATENT OFFICE

DAVID S. BOYLES, OF ROCK HILL, SOUTH CAROLINA

MACHINE FOR MAKING WIRE GARMENT HANGERS

Application filed July 9, 1928. Serial No. 291,238.

The invention has relation to machines for making wire garment hangers, having for an object to provide an improved machine of this description, of great power, and capable 5 of operation at high speed to produce a maximum number of hangers in a given time. Other objects and advantages will hereinafter appear.

The invention consists in the novel construction and combinations of parts as set forth in the appended claims.

In the accompanying drawings illustrating an embodiment of the invention, Figure 1 is a plan view of the invention with the wire bending levers and the twister carriage, both the former and the latter in outward moved position; Figure 2 is a side view of the invention; Figure 3 is a detail plan view of the wire bending levers and operating parts, said levers being in outward moved position; Figure 4 is a similar view, with said levers in inward moved position, the wire being shown as bent to form: Figures 5, 6, and 7 are detail diagrammatic side views of the operating means for the twister carriage, wire bending levers, etc., showing different positions thereof; Figure 8 is a detail side view partly in section of the operating means for the wire blank feeding devices; Figure 9 is a detail plan view of the twister carriage, and Figure 10 is a detail end view of the twister head.

In these drawings the main frame, has 35 supported thereon a horizontal rack 2 for the wire blanks 3, cut to proper length, and fed horizontally and forwardly to the forward end thereof into a vertical offset 4 depending from said rack and including a vertical slot 5 having capacity to receive twelve wire blanks more or less, the lowermost wire blank 3 resting upon the lower of divider blades 6, these wire blanks 3 of wire being released and falling downwardly one at a time by movement of operating rod 7, the forward end of which is pivoted to lower end of arm 8, fast to and depending from rock shaft 9, having fast thereto rocker arm 10 extending above and below the same and at its 50 upper and lower ends having pivoted thereto

links 11, two in number, the forward ends of said links being pivoted to horizontal slides 12, two in number and sliding one above and in contact with the other, the lower slide carrying lower divider blade 6 aforesaid, and the upper slide carrying upper divider blade 6, the rearward movement of operating rod 7 stated causing the lower divider blade 6 to be carried rearward to release lowermost wire blank 3 resting thereon; the upper divider, 60 blade being simultaneously carried forward beneath the vertical series of blanks 3 in slot 5 to support said series, the lower wire so released falling in said slot and coming to rest upon wire blank bending levers 13. In the 65 reverse movement of operating rod 7 the lower divider blade is brought forward beneath the lowermost wire blank 3 to support the series of wire blanks in slot 5, and the upper divider blade is retracted from beneath said wire blanks.

The wire blank bending levers 13 of which there are two, work horizontally and are fulcrumed each at its inner end at 14 to the framing, being provided with upstanding projections 15, 15', shaped to form the upper parts of the hanger, the projections 15 at the free ends of said levers constituting jaws within notches 16 of which the adjacent ends 75 of the wires 3 are received and clamped so that they are securely held against movement, 30 as will be further explained.

The operating means for these levers 13 consists of horizontally working slide 17, 85 working upon guides 18 of the framing and having at one end pivoted links 18' connecting the same with levers 13, power being exerted upon said slide by horizontally working operating lever 19, fulcrumed at 20, and 90 having pivoted link connection 21 with the joint 22 of toggle levers 23, the latter having each pivotal link connection 24 with said slide. Operating lever 19 has stud 19' engaging lateral projection 19'' of rod 7 to move 95 the latter rearwardly to release one wire blank 3, reverse movement of rod 7 taking place by action of its retracting spring 7'. Upon operation of lever 19, the toggle levers 100 will be spread into and slightly past aligned

position from position shown in Figure 3, to position shown in Figure 4, to thereby spread links 24 to a lesser degree, said links 24 having at their forward ends angularly bent portions 24' which in closed position have an angular relation to each other of about 55° and in spread position assume an angular relation to each other of approximately 100°, the toggle levers and said links 24 both working between upstanding frame bearings 25, and the bent portions 24' of said links in spread position taking a fulcrum bearing against the rear sides of bearings 25 to accomplish the finishing pull in bending 15 the wire blank to final garment hanger form.

As a result of the foregoing, the finishing pull in bending the wire blanks 3 to garment hanger form is accomplished very powerfully through the straightening out of the toggle levers into alignment to cause links 24 to take a fulcrum bearing against bearings 25, the work arms of said links (now acting as levers) being quite short compared to the power arms thereof.

25 The wire blanks being bent into final garment hanger form, as stated, the links 24 will be locked against further spreading or movement in one direction by said bearings 25, the toggle levers 23 when moved slightly 30 past aligned position as stated, taking a bearing against a lug 17' of said slide to lock said links 24 against movement in the opposite direction, the wire bending levers 13 being thereby effectually locked in clamping position, to securely hold the wire 3 during the twisting of the free ends thereof, as will be explained. In this position of the parts, any strain of the wire bending and clamping levers 13 tending to release the wire blanks 40 will tend to further press the toggle levers 23 past aligned position, and as this is resisted by lugs 17' of slide 17, the parts are effectually locked as stated.

45 The framing is provided with spaced upstanding projections 25' designed to be located at the ends of the hanger and around which the wire blank 3 is bent to form such ends, said projections being suitably shaped for this purpose, and in order to press and 50 hold inwardly the bottom bar of the hanger during the bending operation slides 26 adjacent projections 25' are moved forwardly. Slides 26 are operated by pawls 27' of levers 27, fulcrumed at 28 and having link connection 29 with lever 30, fulcrumed upon rock shaft 31, said lever 30 having link connection 32 with upstanding lever 33, the latter fulcrumed at its lower end at 34 and at its 55 upper end having link connection 35 with depending lugs 36 of slide 17, the latter forming an operating means for lever 33 and associated parts stated. The slides 26 and the operating parts thereof stated are held in position just as securely as is the slide 17 for 60 the same reasons.

When the wire blank bending levers 13 are brought to final clamping position as shown in Figure 4, the clamping free ends thereof come to rest against frame head 37, the latter being provided with a thin blade or free end 38 which enters within the notches 16 of said levers to force the wire within the same to properly shape and clamp this part of the hanger, the abutting free ends 39 of said levers having notch extensions 16' of and 70 at right angles to notches 16, thereby causing right angle bends 40 to be formed in the wire ends in abutting relation preliminary to twisting the same together as will be explained. As said right angle bends 40 75 are being formed in the end portions of the wire length 3 as stated, said bends 40 at their outer ends will be brought against upstanding divider projection 41 of lever 43, said lever being operated to withdraw said divider 80 projection longitudinally between and without said bends at the same time or shortly after the wire bending levers 13 are brought to final clamping position, the object being to permit the said bends 40 to more gradually come together in parallel opposed contacting relation as shown in Figure 4 rather than to snap together and cross each other as would be likely were this divider device 85 not provided.

90 Operating lever 19 is moved from the position shown in Figures 1 and 3 to the position shown in Figure 4 to move wire bending levers 13 from open to closed position to thereby form the hanger and securely lock the same ready to twist the handle end thereof, the upstanding lever 33 being thereby moved rearwardly and a coiled spring 44 connecting lever 33 with a similar upstanding lever 45 being tensioned, the last named lever being held in forward position at this time, due to link 46 pivotally connecting the upper end thereof with twister carriage 47, said carriage being held in forward position at this time, due to click 48, pivoted to the framing 95 at 49.

100 The hanger being formed ready for twisting as stated, click 48 is released by trip rod 49' pivoted to the lower end of said click at one end and at its other end being hung from arm 50 fast to and carried by rock shaft 31. A coiled spring 51 connected to click 48 serves to normally hold said click in raised position engaging the twister carriage, and upon movement of the trip rod 49 to the position 105 shown in Figure 2 said click is moved downwardly to release said twister carriage against the tension of spring 51.

110 This movement of the trip rod to release said twister carriage takes place automatically at the end of the movement of operating lever 19 to form the wire hanger and securely lock the same ready for twisting.

115 The twister carriage 47 being released as stated will be moved inwardly by tensioned 120

spring 44 to the position shown in Figure 7, pin 52 of upstanding lever 45 being at the same time engaged with lower notch 53 of push rod 54, the latter pivoted at its rear end at 55 to upstanding lever 33.

The twisting of the handle end of the hanger being accomplished as will be explained, operating lever 19 is moved reverse-
ly to the position shown in Figure 3, to open
10 the wire bending levers 13 and return the as-
sociated parts to normal or first position, the
push rod 54 pushing lever 45 to return the
twister carriage to outer position as in Fig-
ures 5 and 6 whereupon the click 48 will be
15 reengaged with the twister carriage to hold
it as moved. At the end of the movement
stated of lever 33, the forward end of push
rod 54 will ride upwardly upon pin 56 of
the framing to the position shown in Figure
20 5 ready to escape from pin 52 when the op-
erating lever 19 and upstanding lever 33 are
again operated.

At the same time that the twister carriage
is moved to inner or twisting position or
25 from position Figure 6 to position Figure 7,
the divider lever 43 is operated by pins 57
of link 46, this movement of the divider lever
being almost simultaneous with the final
clamping movement of the levers 13.

30 The twisting of the approximated wire
ends of the hanger is accomplished by one
half rotation of crank 58, of gear wheel 59,
the latter meshing with pinion 60 upon
35 twister shaft 61, the gear ratio being four to
one and one half turn of crank giving two
turns to twister shaft or head, this giving the
desired twist.

Crank 58 is reversed when the first hanger
40 has been bent into form and handle ends
twisted, hanger removed, succeeding wire
length 3 fed to position, and hanger bent into
form therefrom, when reversal of crank one
45 half turn will twist second hanger, the op-
eration of the parts following rapidly one
after another so that the machine has a large
production capacity.

The twister head or shaft 61 is slotted at
one end at 62 for the reception of two dies 63,
50 divided by means of shims the thickness of
the wire to be twisted, said dies being held in
position by means of set screw 64. The dies
are provided with tapering countersink 65.

In the twisting operation, the length of the
55 ends of the wire being twisted together is re-
duced, and in order to avoid strain and break-
ing of the wire as a result, it is necessary that
the twister shaft 61 move forward slightly
(about one-eighth of an inch). For this pur-
pose there is some end play allowed in
60 twister shaft. Coiled spring 66 is provided
upon twister shaft and bears at one end
against pin 66 of said shaft and at its other
end upon sleeve 67 loose upon said shaft.

65 The pressure of the spring upon the loose
sleeve and pin is adapted to hold the twister

shaft in reverse position, allowing a forward
movement of about one-eighth of an inch.

This almost entirely prevents breakage of
wire during twisting, but as there is an oc-
casional breakage, the sleeve 67 is slotted
70 from end to end and twister shaft is slotted
to permit insertion of small wire to remove
broken pieces.

I claim:

1. In a machine for making wire garment
hangers, means for feeding successive wire
blanks, means for bending said blanks into
form and for locking the bending means in
final clamping position, including levers hav-
75 ing free jaw ends provided with notches hav-
ing right angle extensions, a stationary head
having a blade portion engaging said notches,
the notch extensions being adapted to form
right angle abutting bends in the end por-
80 tions of the wire blanks, and means for twist-
ing the end portions of the blank together
85 while the parts are so locked.

2. In a machine for making wire garment
hangers, means for feeding successive wire
blanks, means for bending said blanks into
90 form and for locking the bending means in
final clamping position including a slide,
spaced abutments, toggle levers, and links
connecting said toggle levers with said slide,
said links being adapted to take a fulcrum
95 bearing against said spaced abutments as said
toggle levers are brought into alignment to
exert a finishing pull in bending the wire
blanks into form, and means for twisting the
100 wire ends together while the parts are so
locked.

3. In a machine for making wire garment
hangers, means for feeding successive wire
blanks, and means for bending said blanks
105 into form including a slide, spaced abutments,
toggle levers, and links connecting said tog-
gle levers with said slide, said links being
adapted to take a fulcrum bearing against
110 said spaced abutments as said toggle levers
are brought into alignment.

4. In a machine for making wire garment
hangers, means for feeding successive wire
blanks, means for bending said blanks into
115 form and for locking the bending means in
final clamping position, and means for twist-
ing the end portions of the blank together
while the parts are so locked, the twisting
means including a reciprocatory carriage
having a head provided with a die for engag-
120 ing the wire ends, and an operating crank
geared to said head to complete the twisting
of a hanger in one half turn of said crank
forwardly and to complete the twisting of a
succeeding hanger in one half reverse turn,
125 and means for holding the carriage in outer
position, for releasing the holding means and
for moving the carriage to inner working po-
sition.

5. In a machine for making wire garment
hangers, means for feeding successive wire
130

blanks, and means for bending said blanks into form having parallel abutting end bends including levers having clamping jaws provided with notches having right angle extensions, and a stationary head having a blade portion engaging said notches proper, the notch extensions being adapted to start right angle bends in the end portions of the blank, and a device movable longitudinally between and without said end bends to facilitate the closing of said bends in parallel abutting relation.

6. In a machine for making wire garment hangers, means for feeding successive wire blanks, means for bending said blanks into form including levers having free jaw ends provided with notches, and a stationary head having a blade portion engaging said notches, the framing having spaced lugs about which the hanger ends are formed, and means for pressing and holding inwardly the bottom bar of the hanger during the bending operation including slides adjacent said spaced lugs and movable towards the same.

7. In a machine for making wire garment hangers, means for feeding successive wire blanks, means for bending said blanks into form including levers and slides, means for twisting the bent ends of the hanger together including a reciprocatory carriage, operating means for said bending levers including an upright lever, means for moving said twister carriage to inner working position including an upright lever having a spring connection with the first named upright lever, means for holding the twister carriage in outer position including a pivoted pawl, means for releasing said pawl to cause the twister carriage to be moved by said spring to inner position, a push bar having connection with the first named upright lever and a lower notch engaging a stud of said last named upright lever for returning the twister carriage to outer position, and a device for releasing said push bar from said stud in the final movement of the upright levers in one direction in returning said clamping levers and twister carriage to first position.

8. In a machine for making wire garment hangers, means for feeding successive wire blanks, means for bending said blanks into form and for locking the bending means in final clamping position, means for twisting the end portions of the wire blank together while the parts are so locked, the twisting means including a reciprocatory carriage having a shaft and a head thereon provided with a die for engaging the wire ends, and an operating crank geared to said head to complete the twisting of a hanger in one-half turn of said crank forwardly and to complete the twisting of a succeeding hanger in one-half reverse turn and means for holding the carriage in outer position, for releasing the holding means and for moving

the carriage to inner working position, said shaft being provided with some end play and having a loose sleeve thereon and a coiled spring bearing at one end against said sleeve, said spring holding said shaft in reverse position and admitting of a slight forward movement of the shaft during the twisting operation.

9. In a machine for making wire garment hangers, means for feeding successive wire blanks, means for bending said blanks into form having right angle end bends and including means for preventing the crossing of said end bends.

10. In a machine for making wire garment hangers, means for feeding successive wire blanks, means for bending said blanks into form having right angle end bends and including means for preventing the crossing of said end bends comprising a device movable longitudinally between and without the said end bends.

11. In a machine for making wire garment hangers, means for feeding successive wire blanks, means for bending said blanks into form having parallel abutting end bends including levers fulcrumed at their inner ends and having at their outer ends clamping jaws provided with notches having right angle extensions, a stationary head having a blade portion engaging said notches, and spaced lugs about which the ends of the hanger are bent by the operation of said levers, the notched ends of said clamping jaws meeting each other and said blade portion to form right angle bends at the roots of said end bends.

12. In a machine for making wire garment hangers, means for feeding successive wire blanks, means for bending said blanks into form having parallel abutting end bends including levers fulcrumed at their inner ends and having at their outer ends clamping jaws provided with notches having right angle extensions, a stationary head having a blade portion engaging said notches, and spaced lugs about which the ends of the hanger are bent by the operation of said levers, the notched ends of said clamping jaws meeting each other and said blade portion to form right angle bends at the roots of said end bends, and means for preventing the crossing of said end bends.

13. In a machine for making wire garment hangers, means for feeding successive wire blanks, means for bending said blanks into form having parallel abutting end bends including levers fulcrumed at their inner ends and having at their outer ends clamping jaws provided with notches having right angle extensions, a stationary head having a blade portion engaging said notches, and spaced lugs about which the ends of the hanger are bent by the operation of said levers, the notched ends of said clamping jaws meeting

each other and said blade portion to form right angle bends at the roots of said end bends, and means for preventing the crossing of said end bends including a lever having an arm fitting between said end bends and means for operating said lever to gradually withdraw said arm from between said end bends.

5 In testimony whereof I affix my signature.
